CLAIM

The ornamental design for a tool container, as shown and described.

DESCRIPTION

FIG. 1 is a perspective view of a tool container showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and,

FIG. 8 is a perspective view thereof in an alternate position. The features illustrated in broken lines in the figures do not form a part of the claimed design.
